UNITED STATES PATENT OFFICE.

MOISE H. DURAND, OF ATTLEBORO, MASSACHUSETTS, ASSIGNOR TO CHARLES D. BLAIKIE, DOING BUSINESS AS SMITH, RICHARDSON CO., OF ATTLEBORO, MASSACHUSETTS.

DESIGN FOR A WOVEN-WIRE FABRIC.

Application filed June 20, 1928. Serial No. 27,208 Term of patent 14 years.

To all whom it may concern:

Be it known that MOISE H. DURAND, a citizen of the United States, residing at Attleboro, in the county of Bristol and State of Massachusetts, has invented a new, original, and ornamental Design for Woven-Wire Fabric, of which the following is a specification, reference being had to the accompanying drawing, forming a part thereof.

Fig. 1 is a plan view of a woven wire fabric embodying my new design.

Fig. 2 is an edge elevation thereof.

Fig. 3 is a reverse plan view thereof.

Fig. 4 is a transverse sectional view thereof.

The inturned side edges shown in Fig. 4 are of substantially the thickness of the center body portion. The woven wire fabric is particularly adapted for use in articles of jewelry, such as wrist watch straps, bracelets, mesh bags, handles, etc.

I claim:

The ornamental design for a woven wire fabric substantially as shown and described.

In testimony whereof I affix my signature.

MOISE H. DURAND.
